LAWN MOWER

Amos F. Moyer, Minneapolis, Minn., assignor to
 Toro Manufacturing Corporation of Minnesota,
 Minneapolis, Minn., a corporation of Minnesota

Application January 27, 1938, Serial No. 187,194

8 Claims. (Cl. 56—294)

This invention pertains to lawn mowers of the type having a plurality of helical knives in the form of a cutting reel, which is revolved in cooperative relation with a stationary knife herein called a bed knife. Such cutting reels are accurately ground and sharpened so that when they are revolved, the cutting edges travel in a cylindrical path, and the function of the bed knife, which is both stationary and straight, is to form a scissor relationship with the helical knives. The bed knife is preferably adjusted so as to form a wiping contact with the helical knives, but may also be adjusted so that a very small clearance is maintained. The precision and uniformity of this contact or minute clearance is a very important factor in the cutting ability of the mower, the maintenance of sharpness of the cutting knives and the bed knife, and in the ease of operation of the mower. Improper adjustment often quickly dulls and destroys the required accurate shape of the cutting edge and even damages the internal grain structure of the metal in the knives to such an extent that they can again be made serviceable only with difficulty.

It is therefore a general object of the invention to provide a bed knife adjusting means of simplified construction that is easy to manipulate and sensitive in the attainable precision of adjustment, and which is capable of being positively locked or retained in adjusted position with the least possibility that the act of locking the same shall alter the adjustment.

In many types of bed knife adjustments presently used, separate screw members are employed, one to urge the bed knife toward the reel and another to urge it away. Each screw when tightened places the intervening members under strain and serves to lock or retain the adjustment against slipping. The final position of the bed knife is uncertain due to the elasticity of the parts, the slack between various members, and the fact that the effect of the adjustment depends both upon which of the adjusting screws is tightened last, and the degree of tightness with which it is tightened. Considerable mechanical skill is, therefore, necessary in order to obtain a satisfactory adjustment with such a mechanism, and the average operator frequently does more harm than good when an attempt is made to adjust the bed knife.

It is accordingly a further object to provide a simplified bed knife adjustment means in which a single adjustment member provides the adjustment of the knife both toward and from the

bar, and in which means are provided for effectively locking such member after adjustment.

More specifically, it is an object to provide such an arrangement in which means are provided for applying pressure to the adjustment member when in adjusted position, and for releasing the pressure during readjustment.

It is a specific object of the invention to provide a mowing machine bed bar adjustment in which a pivotally mounted bed bar is held in cutting relationship with a cutting reel by means of an adjustment screw connecting the bed bar and the machine frame, which screw is held against longitudinal movement and locked against rotary adjustment movement by an integral flange which is held between a suitable locking member and a part of the frame, the pivotal axis being parallel with the cutting edge of the bed knife, and generally disposed rearwardly thereof.

It is another object of the invention to provide a hand operated clamping device for the bed bar adjustment member of a mowing machine.

Other objects and features of the invention are those inherent and suggested by the drawings, and those inherent and suggested by the embodiments of the invention described hereinafter, all of which are features of the invention.

In the description hereinafter given, reference is had to the accompanying drawings in which like characters represent corresponding parts in all views.

Figure 1 is a side elevation of the lawn mower showing the bed knife adjustment device of the present invention;

Figure 2 is a fragmentary section along the lines 2—2 of Figure 1;

Figure 3 is a bottom view of the parts shown in Figure 2;

Figure 4 is a fragmentary enlargement partly in section of the adjusting mechanism shown in Figure 1;

Figure 5 is a side elevation of a modification of the invention;

Figure 6 is a fragmentary view along the line 6—6 of the modification shown in Figure 5; and

Figure 7 is a fragmentary view partly in section along the line 7—7 of Figure 6.

Figure 1 shows a lawn mower of the type in which the cutting reel is propelled by drive wheels of the machine. This construction consists of a frame comprising side plates 1 on which are mounted drive wheels 2. The frame is supported at its trailing edge by a wiper roll 3. Intermediate the drive wheels and the wiper roll 55

there is mounted a cutting reel 4 which is driven by the drive wheels 2 according to the usual practice. The cutting reel consists of a plurality of spiders 5 carrying spiral cutting knives 6. The reel is ground accurately and sharpened so that the cutting edges 7 travel in a circular cylindrical path so as to cooperate with the bed knife 8.

The bed knife 8 is carried by bed bar 9 which is pivotally mounted on side plates 1 by means of screws 10 which pass through holes in the side plates. The screws 10 are of such a size as to fit tightly into boss 11 of the bed bar and also of such a size as to form a closely journaled fit with the holes in side plates 1, and without being in locked engagement with plate 1.

At each of the outer ends of the bed bar 9 there is formed an overhanging lug or protuberance 12 which is threaded so as to receive adjusting screw 13 which is generally parallel with the side plate and passes through a relatively large opening 14 in the side plate lower flange. The upper end of the adjusting screw 13 is provided with a hand wheel 15 by which it may be turned. At an intermediate part of the adjusting screw 13 an integrally formed collar 16 is provided as shown in Figure 4. This collar has a spherical under surface 17 which cooperates with a loosely fitted washer 18 which has one spherical surface 19 and one plane surface 20.

The adjusting screw 13 and spherical washer 18 are held in position by a locking arrangement comprising a forked locking plate 23 which is made of spring steel so as to be slightly flexible, and is shaped so as to have a slight bend and a central aperture 25. The forked end 26 of locking plate 23 straddles the adjusting screw 13 and is held against collar 16 by the action of cam 24 which operates about pivot screw 28 threaded into the side frame 1 at 29. The under surface of the cam 24 is grooved transversely, and when it is in the position shown in Figure 4, the cam groove 27 is parallel with the ridge at the bend in spring plate 23, and thus does not compress the plate, but when the cam is rotated ninety degrees, the cam groove 27 is crosswise of the ridge and hence contacts with and flexes the spring plate downwardly into locking position. The unlocked position of the cam is shown in Figure 4, at which time the cam surface 27 generally parallels the convex upper surface 31 of the forked locking plate.

The upper end of the pivot screw 28 is provided with a plurality of lock nuts 30 which may be adjusted so as to bring the cam surface 27 of hand-operated cam 24 into engagement with the upper surface 31 of the forked locking plate 23. The slight resiliency of plate 23 itself compensates for slight wear, and further wear which may take place between the cam surface 27 of cam 24 and the upper surface 31 of the forked locking plate 23, and wear upon the upper surface of collar 16, may be compensated for by a slight tightening of lock nuts 30. As shown in Figure 1, cam 24 is provided with a hand grip 32 which is arranged so as to be parallel with side plate 1 when the cam surface 27 is in locking position so as not to catch grass and weeds which brush along the side plate 1 when the mower is in operation.

The slight resiliency of plate 23 also insures that the pressure applied to flange 16 for locking screw 13 will be the same save for infinitesimal wear, after successive manipulation of cam 24 to the released position and back to en-

gaged position, and such manipulation therefore causes the knife adjustment to depend only upon the angle through which screw 13 is turned in one direction or the other before locking; whereas in other adjusting and locking devices the final adjustment of the knife depends both upon the angle through which one of the adjusting screws is turned and upon the tightness with which the other screw is locked.

The operation of the adjusting mechanism is as follows:

The hand grip 32 of the cam 24 is rotated away from the frame 1 to a position roughly perpendicular to the side frame 1, as indicated in dot-and-dash lines in Figure 2. When in this position the cam surface 27 will relieve the tension on forked locking plate 23 and thus permit easy rotation of adjusting screw 13 by hand wheel 15. The hand wheel is turned a required or assumed amount and cam 24 returned to engaged position, thereby pressing surface 27 against surface 31 of forked locking plate 23 and flexing the plate to forcibly engage forked end 26 against collar 16. Thereupon, the relationship of cutting edge 33 of bed knife 8, with respect to cutting edges 7 of spiral knives 6 on cutting reel 4 can be checked, and determination made as to whether or not further adjustment of screw 13 by hand wheel 15 is necessary.

The required relationship of the cutting edges depends on one or more of several factors, such as the ease of operation if the mower is pushed by hand, the toughness of grass to be cut, the sharpness of the cutting edges, or the precise circular relationship of the several cutting edges on the reel. If a reel is slightly sprung, as by accidentally striking a hard object at high speed, it is a simple matter by the improved sensitivity of this adjusting means, to cause the bed knife to rub lightly on that part of the spiral knives that may be sprung outwardly and maintain a clearance at other places that is small enough to still cut the grass. Operation of the mower in this condition causes the contacting portion of the spiral knives to wear away, thus restoring a circular form of cutting edges on the reel. A further advantage in the ability to adjust the knives precisely to a very light contact is to produce the well known self-sharpening due to natural wear. It is not so well known, particularly by operators, that the difficulty in manipulating other types of adjustment often causes excessive pressure between the cutting edges. This causes uneven wear and, indeed, local hardening of the metal at certain spots, due to the hammering action that takes place. In consequence, the cutting qualities of the knives are often quickly destroyed by such accidentally produced, but faulty, adjustment. The uncertainties that heretofore have been a prolific cause of such troubles are eliminated by this improved adjustment.

It will be noted that no part of the adjustment mechanism comprising adjustment screw 13, bed bar 9, boss 12, or bed bar mounting screws 10 is placed under stress when the adjustment is in locked position, since the locking force of forked end 26 is concentrated upon collar 16 which directly overlies spherical washer 18, which is in turn in direct contact with surface 20 of the side frame 1. The result is that the locking of the adjustment does not tend appreciably to change the adjustment of the bed knife 8, even if the adjustment of nuts 30 is altered. The spherical surface 19 of washer 18 and the spherical under-

surface 17 of collar 16 permit the adjustment screw 13 to turn and move slightly to accommodate the arcuate motion of bed bar 9 about pivot point 10. Moreover, the cam 24 is closely adjacent the collar 16 whereby a great force is not necessary to effectively lock the adjustment and there is a minimum of elastic deformation in any parts and a freedom from strain imposed on the pivot that would alter the predetermined adjustment.

It will also be noted that the adjustment screw 13 and cam 24 may both be operated from above the mower since the hand wheel 15 and hand grip 32 are accessible from these positions.

Where the mowing machine is of narrow width, such as edging mowers, the bed bar 9 may, if desired, be made of sufficient rigidity that only one adjusting screw 13 is necessary in order to hold the bed knife in correct cutting relationship with respect to reel 4. For greater widths an adjusting screw 13 and cam surfaces 27-31 may be provided at each end of the bed bar 9.

In the modification shown in Figures 5, 6 and 7 the cutting reel 4 is suspended from a super-frame 35 by means of side plate 36, and the cutting reel 4 is driven by means of a suitable gearing from a motor device mounted above frame 35. The gearing and motor have not been shown since they do not form a part of the present invention.

The bed knife 8 is mounted upon bed knife carrying bar 9 which is pivoted to side plates 36 by pivot screws 19 as in the modification previously described. The bed knife carrying bar 9 is formed with an inner boss 37 into which adjusting screw 38 is threaded. Screw 38 passes through a relatively large opening 39 in boss 40 which is formed on the inside of side plate 36 and thus forms a suspension by which the bar is positioned. The adjusting screw 38 is provided with a flange 41 and a slotted head 42.

The locking arrangement in this modification consists of a plate 43 which has a forked end 44 which straddles head 42 and rests against the upper surface 45 of the adjusting screw 38. The locking plate 43 is drawn downwardly against the flange 41 by means of a locking screw 46 which passes through a central aperture 47 of the locking plate and is threaded into the boss 40 at 48.

The operation of this modification of the invention is similar to that shown in Figures 1 through 4, except that the adjusting screw 38 and lock screw 46 are manipulated by means of a screw driver. The locking screw 46 is ordinarily screwed down until the forked end 44 rests tightly against the upper surface 45 of flange 41 on the adjusting screw 38. When a change in adjustment of bed knife 8 is desired the locking screw 46 is loosened slightly so as to relieve the pressure between forked end 44 and upper surface 45 of the flange, at which time the screw 38 may be turned so as to bring the cutting edge 33 of the bed knife into proper relationship with respect to cutting reel 4. After the adjustment has been made, the screw 46 is again pulled down so as to apply pressure between forked end 44 and the upper surface 45 of flange 41, and the adjustment of screw 38 is thereby preserved since the frictional engagement is sufficient to prevent rotation of the screw. The effect of the adjustment made upon the relationship between the knives is then observed.

It will be noted that in this modification also, any variation in the pressure of the locking plate 44 upon flange 41 does not stress that portion of screw 38 which is between the boss 40 of the side

plate 36 and boss 37 on bed knife carrying bar 9. Thus the tightening of the lock screw 46 to one degree or another does not appreciably tend to change the effect of the adjustment which has been made of the adjusting screw. This is important since it permits adjustments to be made with intelligence that is unhampered by obscure mechanical or human factors, and permits an inexperienced operator to readily learn the proper adjustment for his mower.

It is obvious that many changes in details may be made without departing from the spirit of the invention described, and herein claimed. For example, similar principles might be applied for adjustment of movable reel bearings with respect to a stationary bed knife, etc.

I claim as my invention:

1. A bed knife adjustment for a lawn mower having a frame, a cutting reel rotatably mounted on said frame, and a bed knife mounted on said frame for movement into a position for cooperation with said cutting reel, comprising a flanged adjustment screw connecting said bed knife and frame for adjustably positioning said knife with respect to said frame, and clamping means positioned to bear upon said flange.

2. A bed knife adjustment for a lawn mower having a frame having a positioning surface thereon, a cutting reel rotatably mounted with respect to said frame, and a bed knife mounted on said frame for movement into a position for cooperation with said cutting reel, comprising a flanged adjustment screw threaded into said cutting knife and positioned so as to have said flange adjacent said surface, and means for applying pressure as desired to said flange so as to force it into tight contact with said surface.

3. A bed knife adjustment for a lawn mower having a frame having a protuberance thereon, a cutting reel rotatably mounted with respect to said frame, and a bed knife mounted on said frame for movement into a position for cooperation with said cutting reel, comprising a flanged adjustment screw threaded into said cutting knife and positioned so as to have said flange adjacent said frame protuberance, and a fork positioned on said frame so as to engage said flange.

4. A bed knife adjustment for a lawn mower having a frame having a protuberance thereon, a cutting reel rotatably mounted with respect to said frame, and a bed knife mounted on said frame for movement into a position for cooperation with said cutting reel, comprising a flanged adjustment screw threaded into said bed knife and positioned so as to have said flange adjacent said frame protuberance, a fork positioned on said frame so as to engage said flange, and rotary means for forcing said fork into flange engaging relationship.

5. A bed knife adjustment for a lawn mower having a frame, a cutting reel rotatably mounted on said frame, and a bed knife mounted on said frame for movement into a position for cooperation with said cutting reel, comprising an adjustment screw shaft having a screw threaded portion and a circumferential shoulder portion, said screw shaft directly connecting the bed knife and frame with said screw threaded portion threaded into one of them and having said circumferential shoulder portion in abutment with the other of them, and positive stop means pressing on the screw shaft to hold the shoulder portion thus in abutment.

6. A bed knife adjustment for a lawn mower having a frame, a cutting reel rotatably mounted

on said frame and a bed knife mounted on said frame for movement into a position for cooperation with said cutting reel, comprising an adjustment screw shaft having a threaded portion and a circumferential flange portion, said screw shaft directly connecting the bed knife and frame with said screw threaded portions threaded into one of them and having said circumferential flange portion in abutment with the other of them, and

positive stop means pressing on the flange portion to hold the flange portion thus in abutment.

7. The combination set forth in claim 5 wherein in the shoulder portion is a spherical surface.

8. The combination set forth in claim 5 wherein in the means for pressing on the screw shaft is manually actuatable.

AMOS F. MOYER.
